SMOKE DETECTING DEVICE

Alfred L. Mendenhall, Jr., Chicago, Ill.

Application January 17, 1956, Serial No. 559,656

20 Claims. (Cl. 340—237)

My invention relates to an improvement for smoke detector devices and more particularly to a system for continuously monitoring the operation of the components of a smoke detector device. This application is a continuation in part of copending application Serial No. 221,831, filed April 19, 1951, now Patent 2,783,390.

Smoke detector devices as presently used operate on the principle of projecting a beam of light into an atmosphere such as the atmosphere which passes through a ventilating duct which is shielded from extraneous light. Upon the presence of foreign particles such as smoke or dust in an amount exceeding a predetermined amount, the initial light beam is sufficiently altered to activate a light sensitive device which could be a photomultiplier. Since the smoke or dust can be rapidly circulated, it is clear that a single detector will quickly cause the alarm even though the foreign particles are initiated at a point remote from the smoke detector.

In an obscuration type of smoke detector, a light beam can be continuously projected through an atmosphere and into a light sensing device. The presence of smoke or dust in the atmosphere, however, will decrease the amount of light which reaches the light sensing device and thereby change the output of the light sensing device to subsequently activate an indicating device or alarm.

Similarly, in a reflective type of smoke detecting device, a light sensing device is remotely situated to be impinged upon only by light which is reflected or scattered from foreign particles in the atmosphere.

It should be noted that the reflective type of smoke detector is much more sensitive than the obscuration type since the output of the light sensing device, which could be a photomultiplier to achieve freedom from microphonics, goes from an essentially zero value to a finite value, and this difference is easily sensed in commercially available amplifying devices for the subsequent operation of indicating devices.

Until the present time, a major disadvantage of the above type units has been the lack of a simple monitoring system which will monitor the operativeness of the smoke detector elements. That is, since the unit will probably be inoperative over long periods of time (since it may operate only upon the outbreak of a fire), it has been a major problem to assure that the light beam, light sensing device, amplifier and power supply are in an operative condition and that none of the components of the system are burned out or disabled. It is obvious that to assure operativeness of the detecting system is of utmost importance since a failure of a smoke detector may result in an uncontrolled fire and all of its consequences.

It is to be noted that monitoring of smoke detector devices has been attempted but has always been directed to systems for assuring operativeness of tube filaments and the bulb filament.

Clearly this type of monitoring is undesirable in that the other components of the device can fail although

2

the various filaments are operative and the system would be incapable of activating alarms responsive to the presence of smoke.

The principle of my invention is to continuously monitor the operation of the components of a smoke detecting device by producing a second light beam which is produced in a manner to make it distinguishable from the first light beam, the first light beam being used for the actual smoke detection, and to continuously impinge the second or monitoring light beam upon the light sensing device of the smoke detector whereupon the output signal of the amplifier associated with the light sensing device will selectively operate (since the output signal due to the second light beam is distinguishable from that due to the first light beam) an indicating device to indicate normal operation.

Hence, upon the presence of foreign particles in the atmosphere being protected, the first light beam will be impinged upon the light sensing device which could be a photomultiplier, and the amplifier output signal which is distinguished from that due to the monitoring light beam can be used to activate an alarm or second indicating device.

Since the second or monitoring light beam can be initiated from the source of the first light beam and thereafter altered to be distinguished from the first light beam, my novel monitoring system will therefore continuously monitor the operation of each of the light source, photocell, amplifier, amplifier output filter (if used), and the power supply which normally energizes the above components. A failure of the monitoring system or the components of the smoke detector will therefore be substantially instantaneously indicated by the indicating device which can indicate normal or abnormal operation of the complete system.

More specifically, I can make the first or particle detecting light beam distinguishable from the second or monitoring light beam by dividing the light from a light source into two beams and thereafter interrupt the first light beam a first predetermined number of times per second, and interrupt the second light beam a second predetermined and different number of times per second. Obviously, this is only one of many acceptable ways of varying the first and second light beam in such a way as to produce electrical signals responsive thereto for selectively operating indicating devices. That is, it would be conceivable to utilize the modes of polarization or frequencies to distinguish between the first and second light beams without departing from the principle of my invention.

The use of a chopped light beam for at least the first or smoke monitoring beam, however, provides certain advantages which allow a high level of sensitivity for the smoke detecting device. As was previously mentioned, the second or monitoring light beam is so diverted that it is continuously impinged upon a light sensing device such as a photomultiplier whereas the first or smoke detecting beam is so directed that (in a reflective type smoke detector) it will impinge upon the photomultiplier only when reflected or scattered by foreign particles. Therefore, the intensity of reflected light in the presence of a few foreign particles will be very low. However, by providing a chopped light beam for the smoke detection beam the output of the photomultiplier due to the low intensity of reflected light will be in the form of a pulse, the frequency of which is the frequency at which the light beam is being interrupted.

Hence the photocell output can be applied to an A. C. amplifier or if desired can be directly applied to circuits which are resonant to this frequency. As a typical example the phototube output can be applied to an A. C. amplifier and the output of the A. C. amplifier can be

passed through narrow band circuits which in turn are connected to the resonant devices. Obviously this system will result in a very high signal-to-noise ratio.

Similarly, when the second or monitoring light beam is of the chopped type, the resultant photomultiplier output will once again be an A. C. current which differs in frequency from that due to the first or smoke detecting light beam and if desired can be passed through the amplifier, the narrow band circuits and subsequently to devices which are resonant to the frequency of the A. C. current due to the second light beam. Once again, the desired high signal-to-noise ratio is provided.

It is now clear that the signal due to the second or monitoring light beam continuously monitors the operation of the amplifier which is also used to amplify the signal due to the first or smoke detecting light beam upon the detection of foreign particles in the atmosphere being protected. The output of the amplifier will normally be of the frequency determined by the monitoring light beam and it is obvious that this output can be used to activate an indicating device which is responsive to that particular frequency or, if desired, to its rectified output to allow the use of D. C. activated indicating devices.

Similarly upon the occurrence of foreign particles in the atmosphere being protected, the A. C. output of the amplifier will be at the characteristic frequency of the smoke detecting light beam and this frequency may then be used to operate an indicating device which is operable only by that particular frequency.

This indicating device could in itself be an alarm, if desired could trigger alarms which are placed at points remote from the area being protected. As an alternative, or in addition to the indicating devices used in the immediate vicinity of the smoke detecting device, both the monitoring output signal and the particle detecting signal could be fed through the lines of an organization such as the American District Telegraph and to their control office alarm station where the monitoring signal will perform the additional function of monitoring the A. D. T. lines. When, however, the alarm signal is received at the A. D. T. office, it will serve to initiate their function.

Accordingly, a primary object of my invention is to provide a system for continuously monitoring the operation of each component of a smoke detecting device.

Still another object of my invention is to provide a second light beam which is distinguishable from the light beam which is used for smoke detection and to impinge the second light beam upon the light sensitive device of a smoke detecting system whereupon continuous operation of the excited light sensing device, its associated amplifier, power supply and indicating device will be assured.

Still another object of my invention is to provide a monitoring light beam for a smoke detector device which is distinguishable from the smoke detecting light beam and is initiated from the same source which initiates the smoke detecting light beam.

Still another object of my invention is to provide a first and second light beam for a smoke detector device wherein these beams are interrupted a different number of times per second, one of the light beams being used for smoke detection and the other light beam being used to assure continuous operation of the smoke detection device.

Still another object of my invention is to provide a smoke detector having a monitoring light beam which continuously energizes operation of a light sensitive device such as a photomultiplier and its associated amplifying and indicating devices.

A still further object of my invention is to provide a smoke detecting device wherein a photomultiplier will have a continuous A. C. output signal of one frequency and the occurrence of foreign particles will initiate an A. C. signal of a second frequency.

A still further object of my invention is to use a first or smoke detecting light beam and a second or monitoring light beam, each of which is interrupted at a different frequency to subsequently impart an A. C. output for their associated photomultiplier wherein the output frequencies are distinguishable from one another and circuits responsive to these frequencies are provided to actuate indicating devices.

My invention also contemplates a system whereby a constant smoke or particle detection level is maintained. It has been found that with presently used devices that the system sensitivity or detection level changed due to amplifier drift and changes in intensity in the detecting light beam. Hence, due to the accumulation of dust on the various reflecting surfaces or a decrease in the light intensity of the light source or the like, a given particle density will reflect less light into the light sensitive device.

I have overcome this disadvantage by providing an amplifier which delivers a constant output for a wide range of input signals. One method by which this can be done is by using an amplifier having an automatic gain control circuit of well known design.

It is to be clearly noted that this type of system can now be used to great advantage in view of the additional monitoring light beam of my invention. That is, the intensity level of the monitoring beam can be compared to the intensity of the detecting beam which is reflected from a predetermined density of foreign particles.

Clearly, therefore, if the monitoring light beam intensity is cut down or if the amplifier drifts, signals due to the monitoring light beam (as well as the signal due to the light which would be reflected by foreign particles) will be amplified by a greater amplification factor. Hence, upon the reflection of light by foreign particles, the amplification factor of the amplifier will be pre-adjusted to give a predetermined output for the decreased smoke detection signal.

It is therefore seen that the sensitivity of my novel unit can be controlled by adjusting the intensity of monitoring light since it is this value that adjusts the amplification factor of the amplifier. If, for example, this intensity is small, then the amplification factor of the amplifier will be high and a small amount of reflected light will be detected. Conversely, if the monitoring light is made more intense, the amplifier amplification factor will be decreased to decrease the level of sensitivity of the unit reflected light.

Accordingly, an ancillary object of my invention is to provide a smoke detector of the type having a monitoring light beam wherein the intensity of the monitoring light beam varies the amplification factor of the amplifier.

Still another object of my invention is to provide a smoke detector whereby the intensity of the monitoring light beam is adjusted to the intensity of light which is reflected from a minimum predetermined amount of foreign particles.

Another object of my invention is to provide a smoke detector whereby the intensity of a monitoring light beam varies the amplification factor of the amplifier to thereby assure a signal due to the smoke detecting beam being reflected from a predetermined density of foreign particles even though the intensity of the smoke detecting beam is decreased.

These and other objects of my invention will become apparent from the following description taken in connection with the drawings in which:

Figure 1 shows a perspective view of smoke detector which contains my novel monitor system.

Figure 2 shows a top view of Figure 1 and further locates many of the associated components of the smoke detector.

Figure 3 is a block diagram which indicates how the

first and second signals, one being the monitoring signal and the other being the alarm signal, are taken from the photocell to their subsequent indicating devices.

Figure 4 shows a detailed diagram of an amplifier and associated components which may be used for the block diagram of Figure 3.

Figure 5 shows a detailed diagram of a photomultiplier which is used in accordance with my invention.

Figure 6 shows a detailed diagram of an annunciator panel which can be activated by the smoke detector 10 of my device.

Figure 7 shows a typical power supply which can be used to energize the components of the smoke detector device of my invention.

Referring now to Figures 1 and 2, an air duct 10 conducts an air flow which is generally shown by the arrows. The duct entrance 11 can if desired contain a sail switch to indicate air flow and a device such as the fan 12 causes this air flow. Obviously this is only to indicate that my smoke detector device will be applied in an environment wherein a changing atmosphere is available and the construction shown herein is for illustrative purposes only.

The smoke detecting apparatus is shown as being generally housed within the housings 13 and 14 and the top of these housings 13 and 14 as well as a portion of the top of the duct 10 is shown in a cut away view to afford observation of the essential smoke detector components.

Within the housing 13 there is shown a light source 15 which is illuminated by means of the electrical terminals 16 and 17. These terminals are of course energized in any desirable manner and the energizing means is now shown herein. The light of the light source 15 of course radiates in all directions but interest is directed here only in the directions indicated by the dot-dash lines. That is, a first light beam 18 is directed towards an outer series of holes 19 of disk 20 and a second light beam 21 is reflected by means of a reflecting device such as a mirror 22 and then passed through a lens 23 which can be used to adjust the light intensity and is thereafter directed upon a second series of holes 24 which are inwardly positioned with respect to the holes 19 of the disk 20. As will be shown hereinafter, the smoke detector of Figures 1 and 2 is further constructed to allow the light beams 18 and 21 access to duct 10 in a manner to exclude extraneous light. It is also to be noted that light beams due to source 15 which are in a random direction are prevented from having access to the disk 20 by means of the wall 13a which has apertures 18' and 21' therein. Clearly, the apertures 18' and 21' are then positioned to allow only the light beams 18 and 21 to be impinged upon the disk 20.

The disk 20 is then rotated at a predetermined speed by means of a motor and associated gear box which is shown schematically as the motor 25. The output shaft 26 of motor and gear box 25 is fastened in any desired manner to the center of the disk 20 at the point 27. For illustrative purposes only, it is seen in Figure 1 that this fastening is accomplished by means of a plate 28 which is attached to shaft 26, this plate being maintained on the disk 20 by means of screws 29.

It is clear, however, that is is only desirable to rotate the disk 20 in such a manner as to allow the outer holes 19 and the inner holes 24 to interrupt the first light beam 18 and the second light beam 21 and this could be accomplished in any number of ways. Obviously, the interruption frequencies will be determined by the rotational velocity imparted to disk 20 by means of the motor 25 and by the number of holes 19 which interrupt the light beam 18 and the number of holes 24 which interrupt the light beam 21.

As an example, in a commercial embodiment it has been found practical to construct these associated elements in such a manner as to provide an interrupted

frequency of 210 cycles per second for the monitoring light beam 21 and an interrupted frequency of 289 cycles per second for the smoke detecting beam 18. Clearly, however, these are merely two illustrative values and they need not be used to practice my novel invention.

The first light beam 18 as is further shown in Figures 1 and 2 is impinged upon a collimator 30 after being interrupted by the rotated apertures 19. Collimator 30 is fastened in such a manner as to direct the light beam 18 through the wall of the housing 13 and into the air duct 10, this light beam 18 now being made a parallel beam of light. As is shown, the two lenses of the collimator are positioned to afford a minimum amount of aberration in the paralleled light beam. The collimator 30 is further provided with baffles 30a which are so positioned as to enhance the confining of light beam 18 to a parallel beam. The baffles 30a are more particularly constructed so that each preceding baffle 15 "shadows" the next to thereby decrease the secondary source reflection and assure a more parallel light beam at the output of the collimator. Clearly, however, the collimator 30 is but one example of many acceptable systems which could be used to parallel the light beam 18.

After passing through the wall of the duct 10, the light beam 18 is then impinged upon the other side of the air duct 10 which is so constructed as to perform a blackbox like function. That is, by providing baffles 31 in a suitable manner, the parallel light beam 18, which can now be recognized as the light beam which will detect the presence of foreign particles in the air flowing through the duct, will normally not be reflected from the wall of the air duct 10.

The second light beam 21, which can be shown as forming the monitoring light beam of my novel invention, is impinged upon a light conducting tube such as the tube 32 (which may be constructed of Lucite) after passing through apertures 24.

Then the light beam 21 will be conducted through the Lucite tube 32 which is constructed to pass from the housing 13 and into the air duct 10 to subsequently direct the beam 21 at a substantial right angle to the particle detecting beam 18 and into a mirror 33 which projects into the air duct 10 from the housing 14.

A light sensitive device 34 is positioned within the housing 14. Although device 34 could be a photoelectric cell or phototube or any of such light sensitive devices, I will arbitrarily refer to the device 34 as a photomultiplier. Hence, it is seen that the light beam 21, which is the light beam to monitor the operation of the smoke detecting device, is continuously impinged upon the photomultiplier 34.

Clearly, the light beam 21 could have been brought to continuously impinge upon the photomultiplier 34 or any other similar light sensing device in many acceptable ways such as by using reflective type devices to guide the light beam and the system shown herein is merely an example of one of these many ways.

It has been noted that under normal operating conditions the light beam 18 is conducted into the air duct 10 where it is impinged upon a light baffle device 31 to prevent any reflection. Assuming now that a foreign particle such as the particle 35 enters the air duct 10, it is clear that a portion of light beam 18 which impinges upon this particle can be reflected or scattered as is shown by the reflected beam 18a into the mirror 33 and subsequently into the photomultiplier 34. Therefore, if the light beam 18a is interrupted at a frequency which is different from that of the frequency at which the light beam 21 is interrupted, the output of the photomultiplier 34 will not only be at the interrupted frequency of the monitoring light beam 21 but will also be at the interrupted frequency of the light beam 18a which

of course is the same as the frequency of the light beam 18.

It has now been shown that the photomultiplier 34 of Figures 1 and 2 will, during normal operation of each of the components mentioned heretofore (light source, motor, power supply, etc.) have an output of a frequency given by the interrupted frequency of the monitoring light beam 21. However, upon the occurrence of a foreign particle such as 35 which could be smoke or dust, the interrupted frequency of the light beam 18 will then be superimposed upon the output of the photomultiplier 34. Clearly, however, failure of any of the components which operate on the light beam 18 will result in a loss of the signal due to the monitoring light beams 21 which will subsequently indicate inoperativeness of the device.

Figure 3 indicates how the output of the photo-multiplier 34 can be taken from the photo-multiplier and to the subsequent indicating devices. As is shown in the block diagram of Figure 3, the photo-multiplier 34 feeds its signal to the input of an A. C. amplifier 37. The output of the amplifier is then taken to a filter 38 and from the filter the signals branch off to a device 39 which could be a relay which is operable only by the interrupted frequency of the smoke detecting light beam 18 and to a rectifying device 40. The filter 38 contains narrow band circuits which, as was previously mentioned, operate to improve the signal to noise ratio of the system.

Hence, the rectifying device 40 which is always operative in view of the continuous impingement of the monitoring light beam 21 upon the photo-multiplier 34 can be used to activate a D. C. relay 41 which in turn can be used to operate an indicating device 42 which will indicate normal operation of the system.

Similarly, the relay 39 which is operable only in response to the detection of foreign particles within the duct 10 is then operable to energize a device 43 which can be an alarm device.

Therefore, during normal operation, a light beam 21 initiated by the light source 15 of Figures 1 and 2, is interrupted at a predetermined frequency by means of holes 24 of disk 20 and is subsequently lead by means of a Lucite tube 32 to impinge upon a mirror 33 and to thereafter activate the photomultiplier 34. This characteristic frequency is then as is shown in Figure 3 applied by the photomultiplier 34 to the amplifier 37, filter or narrow band pass circuits 38, rectifier 40, relay 41 and the indicating device 42 which indicates normal operation. Since the relay 39 is responsive only to the characteristic interrupted frequency of the smoke detecting beam 18, this relay will not be operated and the alarm device 43 similarly will not be operated.

However, upon failure in either the light source 15, motor 25 which rotates the disk 20, photomultiplier 34, amplifier 37, filter and narrow band circuits 38, rectifier 40, relay 41 or the power supply energizing the above devices, then the indicating device 42 will lose its signal to thereby indicate to operating personnel that the smoke detecting device is inoperative.

Upon the presence of foreign particles in the duct 10, the light beam 18 which uses all of the above mentioned components which are continuously monitored by the monitoring beam 21 will immediately cause the operation of the relay device 39 of Figure 3 which is responsive only to the characteristic interrupted frequency of the light beam 18 to thereby cause an alarm or indicating device 43 to be energized.

Therefore, it is seen that in using my novel monitoring system, all of the components of the smoke detector must be operable to avoid the operation of a monitoring indicating device. It is to be noted, however, that the smoke alarm indicators are not (due to their inherent nature) monitored. However, it is feasible to assure operativeness of even these components by purposely actuating them at predetermined intervals.

It is to be emphasized at this point that the preceding

explanation involves only one of the many possible embodiments which my novel principle can assume. Hence, it is possible to use different colored light beams, one for detecting a change in color of a medium and the other for monitoring the operation of the system. Similarly, the density of a gas beyond predetermined limits may be detected by a reflected or refracted light beam and a second light beam could monitor the operation of the system.

Clearly, there are applications which would not necessitate the use of a housing such as the housing 10 for an air duct wherein the particle detector could be preset to give alarm when the density of foreign particles in the surrounding medium is different from some predetermined amount.

The components referred to in the block diagram of Figure 3 are more specifically shown in conjunction with the Figures 4, 5, 6 and 7 where Figure 4 contains the amplifier, narrow band circuits and indicating devices, 20 Figure 5 shows the motor, lamp and photomultiplier, Figure 6 shows the annunciator panel and Figure 7 is the power supply. It is seen that the components of the figures are mutually interwired and that the figures are clearly set apart from one another by means of the heavy dot dash lines. Hence, the terminal block 50 to which the various voltages created by the power supply of Figure 7 are applied are similarly applied to terminal block 51 of Figure 5. In a like manner, the voltages appearing on the terminal block 52 of Figure 5 also appear on terminal block 53 of Figure 4.

The output of photomultiplier 54 of Figure 5 is shown as being applied to the amplifier proper which in Figure 4 may be generally seen as comprising the tubes 57, 58 and 59. The output of the amplifier shown in Figure 4 is then applied to the narrow band pass circuits or filter shown generally at 60, the output of filter 60 being rectified in the rectifier 61 and being supplied to the relay 62 which is responsive only to the frequency of the signal obtained under smoke detection conditions. Other relays shown 40 as relays 63, 64, 65 and 66 as will be shown hereafter contribute to the selective function of the system proper for indicating normal operation of the signal due to foreign particles.

It is to be noted that the amplifier of Figure 4 is provided with automatic grid control circuits. This has been found desirable in practical applications since the intensity of light impinging upon photomultiplier 54 of Figure 5 is variable in view of dust accumulation on reflector surfaces etc. Therefore, the provision of the 45 automatic grid control circuits in the amplifier allows an output signal (with respect to the monitoring light beam) of constant magnitude.

This feature also allows the adjustment and maintenance of a constant sensitivity line. That is, by adjusting the intensity of monitoring light, the amplification factor of the amplifier is determined and the signal due to reflection of scattering of the detecting beam required to operate its indicating device is similarly determined. If it is desired to increase this intensity it is only required 50 that the intensity of the monitoring light beam be decreased to thereby increase the amplification factor of the amplifier. Similarly, the sensitivity can be decreased by increasing the intensity of the monitoring light beam.

In order to maintain a desired sensitivity level, even 55 though the intensity of the beams will be changed due to dust accumulation etc., it is only necessary that the monitoring light beam be adjusted to the intensity of light which would be reflected from a predetermined density of foreign particles, this level being constantly maintained by automatic grid control circuits even though the intensity of the light beam is varied.

As a further feature of the complete smoke detector, Figure 5 also shows how electrical connections may be made to a detector service connector wherein the vital 60 parts of the amplifier and the relay system may be moni-

tored from outside means at any time. In Figure 5 a detector terminal strip 67 is connected to the various output circuits of Figure 4, these output signals being subsequently applied to the annunciator shown specifically in Figure 6 at the terminal strip 68 whereupon various indicating devices may be operated in accordance to predetermined conditions.

It is to be clearly noted that the components shown in Figure 4 through Figure 7 are intended to merely indicate the type of units which could be used in the block diagram of Figure 3 and many variations could result in substantially the same operation. A detailed description is not deemed necessary here since all of the components are old and well known.

The sequence of operation, however, entailed in the use of components such as those in Figure 4 through 7 is as follows: To initiate operation, the main switch shown as switch 69 of Figure 6 is closed to thereby light the power on lamp 70, the trouble signal lamp 71, trouble buzzer 72 and relay 73 of Figure 7. Upon operation of relay 73 the motor shown generally at 74 (which rotates disk 20 of Figure 1) begins to operate and the transformer 75 of Figure 7 is energized. Transformer 75 then supplies power to the amplifier shown generally in Figure 4, the photomultiplier 54 of Figure 5, and the light source 76 of Figure 5 (which will subsequently send out the first and second light beams or the monitoring and smoke detector light beams). Photomultiplier 54 therefore will be impinged upon by the monitoring light beam as was shown in Figures 1 and 2 to thereby supply a predetermined signal to the amplifier of Figure 4.

Upon amplifier operation, it is clear that the relay 66 will be energized but since the frequency of the amplifier output is that due to the monitoring light beam and relay 64 will not operate. Operation of relay 66 subsequently causes the relay 65 to operate and also causes the relay 77 of Figure 7 to operate which thereby parallels contact 78a and 78b of relay 78 to subsequently operate relay 79 of Figure 6 in the annunciator panel. Upon operation of relay 79 of Figure 6 it is apparent that the normal operation lamp 80 will operate and the trouble lamp 71 and trouble buzzer 72 will be de-energized. After a predetermined time which begins with the operation of the manual switch 69, the relay 78 (which has a time delay) will operate to thereby ground the cathode of the photomultiplier tube 54 and take the parallel circuit off the contacts 78a and 78b of the relay 78. Hence, the system is now operating accordingly in a normal manner.

Assume now that the beam of light which is the smoke detecting beam of light (light beam 18 of Figure 1) detects a particle in the duct through which the atmosphere being protected is flowing. Clearly then the photomultiplier 54 will be energized to have an output frequency different from that from which it normally delivers due to the impingement thereon of the monitoring light beam. Hence, the second detecting signal will be amplified in the amplifier of Figure 4 to thereafter operate the relay 62 which is so constructed as to be energized for operation responsive only to the particular frequency which is characteristic of the smoke detecting light beam. By providing the narrow band pass circuits 60, this selective effect is enhanced since the signal to noise ratio is considerably increased. Operation of the relay 62 causes the subsequent operation of relay 63 which in turn operates the relay 64. Relay 64 thereafter causes the smoke alarm light and bell 81 and 82, respectively, in Figure 6 to operate and also causes the relays 83 and 84 to allow energization of their external circuits which can be attached to other alarm or indicating devices at terminal block 85.

If desired, the relays 83 and 84 may be latching relays. If this is the case, a push button 86 can be provided to allow clearing of the relays 83 and 84, and a switch 87 can be similarly provided to allow manual

recycling to achieve the alarm a second time to thereby test the operation of the circuit.

In the preceding explanation it was apparent that the use of my novel monitoring system assured that the power supply, the photo-multiplier, amplifier, relays, and the filter were in operating condition prior to the occurrence of an alarm. As a further addition to my novel system, it is apparent that the annunciator devices can be of the normally on type, and the currents of the monitoring signal maintaining these normally on devices in their off position. Therefore, upon failure of the annunciator device, it will go to its on position which may be energized by battery means to thereby be independent of a power source for indication of inoperativeness in the indicating devices or system.

In the foregoing, I have described my invention only in connection with preferred embodiments thereof. Many variations and modifications of the principles of my invention within the scope of the description herein are obvious. Accordingly, I prefer to be bound not by the specific disclosure herein but only by the appending claims.

I claim:

1. A smoke detecting device for detecting the presence of foreign particles in a volume of air which is to be circulated through a duct wherein the smoke detecting device has access to the air passing through said vent in a manner to exclude extraneous light from the duct, said smoke detecting device comprising a light source for projecting a first and second light beam, an interrupting means to interrupt said first light beam a first predetermined number of times per second and to interrupt said second light beam a second predetermined number of times per second, a photomultiplier, an amplifier, a narrow band pass circuit, a first and second indicating device and energizing means being connected to energize operation of said light source, photomultiplier and amplifier; said first light beam being directed with respect to the position of said photomultiplier to be impinged upon said photomultiplier only upon reflection and scattering from foreign particles in said atmosphere, said second light beam being directed to continuously impinge upon said photomultiplier; the output of said photomultiplier, being connected to the input of said amplifier, the output of said amplifier being passed through said narrow band circuits and thereafter to said first and second indicating devices; said first indicating device being constructed to be operative when said amplifier output contains at least the interrupted frequency of said first light beam, said second indicating device being constructed to be operative when said amplifier output contains at least the interrupted frequency of said second light beam, said second light beam being a monitoring light beam for assuring continuous operation of at least said light source, photomultiplier, amplifier and energizing means.

2. A smoke detecting device for detecting the presence of foreign particles in a volume of air which passes through a duct, the said smoke detecting device having access to the air passing through said duct in a manner to exclude extraneous light; said smoke detecting device comprising a light source for projecting a first and second light beam, an interrupting means to interrupt said first light beam a first predetermined number of times per second and to interrupt said second light beam a second predetermined number of times per second, a photo-multiplier, an amplifier, a first and second indicating device and means for energizing said light source, photo-multiplier and amplifier; said first light beam being directed with respect to the position of said photo-multiplier to be impinged upon said photo-multiplier only upon reflection from foreign particles in said atmosphere, said second light beam being directed to continuously impinge upon said photo-multiplier; the output of said photo-multiplier being connected to the input of said amplifier,

the output of said amplifier being connected to said first and second indicating devices; said first indicating device being constructed to be operative when said amplifier output contains at least the interrupted frequency of said first light beam, said second indicating device being constructed to be operative when said amplifier output contains at least the interrupted frequency of said second light beam, said second light beam being a monitoring light beam for assuring continuous operation of at least 10 said light source, photo-multiplier, amplifier and energizing means.

3. A smoke detecting device for detecting the presence of foreign particles in a volume of air, means being provided to circulate the said volume of air through a vent; the said smoke detecting device having access to the air passing through said vent, said smoke detecting device comprising a light source for projecting a first and second light beam, an interrupting means to interrupt said first light beam a first predetermined number of times per second and to interrupt said second light beam a second predetermined number of times per second, a light sensing device, an amplifier, and a first and second indicating device; said first light beam being directed with respect to the position of said light sensing device to be impinged upon said light sensing device only upon the presence of foreign particles in said air, said second light beam being directed to continuously impinge upon said light sensing device; the output of said light sensing device being connected to the input of said amplifier, the output of said amplifier being connected to said first and second indicating devices; said first indicating device being constructed to be operative when said amplifier output contains at least the interrupted frequency of said first light beam, said second indicating device being constructed to be operative when said amplifier output contains at least the interrupted frequency of said second light beam, said second light beam being a monitoring light beam for assuring continuous operation of at least said light source, light sensing device and amplifier.

4. A smoke detecting device for detecting the presence of foreign particles in a volume of air which is circulated through a duct; the said smoke detecting device having access to the air passing through said duct, said smoke detecting device comprising a light source for projecting a first and second light beam, means to vary said first and second light beam according to a first and a second mode, a light sensing device, an amplifier, and a first and second indicating device; said first light beam being directed with respect to the position of said light sensing device to be impinged upon said light sensing device only upon its reflection from foreign particles in said air, said second light beam being directed to continuously impinge upon said light sensing device; the output of said light sensing device being connected to said first and second indicating devices; said first indicating device being constructed to be operative when said amplifier output contains at least the mode of variation of said first light beam, said second indicating device being constructed to be operative when said amplifier output contains at least the mode of variation of said second light beam, said second light beam being a monitoring light beam for assuring continuous operation of at least said light source, light sensing device and amplifier.

5. A smoke detecting device for detecting foreign particles in air; said smoke detecting device comprising a light source for projecting a first and second light beam, means to vary said first and second light beam according to a first and a second mode, a light sensing device, an amplifier, and a first and second indicating device; said first light beam being directed with respect to the position of said light sensing device to be impinged upon said light sensing device only upon the presence of foreign particles in said air, said second light beam being directed to continuously impinge upon said light sensing device; the output of said light sensing device being connected to

the input of said amplifier, the output of said amplifier being connected to said first and second indicating devices; said first indicating device being constructed to be operative when said amplifier output contains at least the mode of variation of said first light beam, said second indicating device being constructed to be operative when said amplifier output contains at least the mode of variation of said second light beam, said second light beam being a monitoring light beam for assuring continuous operation of at least said light source, light sensing device and amplifier.

6. A smoke detecting device for detecting the presence of smoke in air which is drawn through a duct comprising a synchronous motor, a disk having apertures therein being driven by said synchronous motor, a light source, a photomultiplier, means to amplify the output of said photomultiplier and a first and second indicating device connected to said amplifier, said light source being constructed to provide a first and a second beam of light, said motor driven disk apertures being positioned relative to said first and second beam of light to synchronously interrupt said first beam of light in a first predetermined manner and to synchronously interrupt said second beam of light in a second predetermined manner upon rotation of said disk; said first interrupted beam of light being introduced into said duct in such a direction as to be reflected into said photomultiplier when smoke is drawn through said duct, said second interrupted beam of light being constantly impinged upon said photomultiplier; said first indicating device constructed to be operated when the amplified output of said photomultiplier is due to said first interrupted beam of light, said second indicating device constructed to be operated when the amplified output of said photomultiplier is due to said second interrupted beam of light.

7. A smoke detecting device for detecting the presence of smoke in air comprising a motor, a disk having apertures therein being driven by said motor, a light source, a photo-multiplier, means to amplify the output of said photo-multiplier and a first and second indicating device connected to said amplifier; said light source being constructed to provide a first and a second beam of light, said motor driven disk apertures being positioned relative to said first and second beam of light to synchronously interrupt said first beam of light in a first predetermined manner and to synchronously interrupt said second beam of light in a second predetermined manner upon rotation of said disk; said first interrupted beam of light being directed to be reflected into said photo-multiplier when smoke is present in the air, said second interrupted beam of light being constantly impinged upon said photo-multiplier; said first indicating device being constructed to be operated when the amplified output of said photo-multiplier is due to said first interrupted beam of light, said second indicating device being constructed to be operated when the amplified output of said photo-multiplier is due to said second interrupted beam of light.

8. A smoke detecting device for detecting the presence of smoke in air comprising a motor, a disc being driven by said motor, a light source, a light sensing device, means to amplify the output of said light sensing device and a first and second indicating device connected to said amplifier; said light source being constructed to provide a first and a second beam of light, said motor driven disc being connected to synchronously interrupt said first beam of light in a first predetermined manner and to synchronously interrupt said second beam of light in a second predetermined manner; said first interrupted beam of light being directed to impinge upon said light sensing device responsive to the presence of smoke in the air, said second interrupted beam of light being constantly impinged upon said light sensing device; said first indicating device being constructed to be operated when the amplified output of said light sensing device is due to said first interrupted beam of light, said second indicating de-

vice being constructed to be operated when the amplified output of said light sensing device is due to said second interrupted beam of light.

9. A smoke detecting device for detecting the presence of smoke in air comprising a motor, a disk being driven by said motor, a light source, a light sensing device, means to amplify the output of said light sensing device and a first and second indicating device connected to said amplifier; said light source being constructed to provide a first and second beam of light, said disk being constructed to synchronously interrupt said first beam of light according to a first frequency and to synchronously interrupt said second beam of light according to a second frequency upon rotation of said motor; said first interrupted beam of light being directed to be reflected into said light sensing device when smoke is present in the air, said second interrupted beam of light being constantly impinged upon said light sensing device; said first indicating device constructed to be operated when the amplified output of said light sensing device is due to said first interrupted beam of light, said second indicating device constructed to be operated when the amplified output of said light sensing device is due to said second interrupted beam of light.

10. In a device for detecting particles in an atmosphere comprising a light source, means to vary the light of said light source according to a first and second mode, a light sensing device and alarm means, the light of said light source being varied according to said first mode being directed to continuously impinge upon said light sensing device and the light of said light source being varied according to said second mode being directed to be impinged upon said light sensing device by reflection from said particles to be detected, said alarm means being constructed to be actuated upon the loss of the signal due to said light being varied according to said first mode, said alarm means being further constructed to be actuated when the output of said light sensing device is partially due to said light means being varied according to said second mode.

11. In a device for detecting changes in the reflectivity of a gaseous medium comprising a light source, means to vary the light of said light source according to a first and second mode, a light sensing device and alarm means, the light of said light source being varied according to said first mode being directed to continuously impinge upon said light sensing device and the light of said light source being varied according to said second mode being directed to be impinged upon said light sensing device by reflection from said gaseous medium, said alarm means being constructed to be actuated upon the loss of the signal due to said light being varied according to said first mode, said alarm means being further constructed to be actuated when said light sensing device is impinged upon by said light varying according to said second mode of an amount greater than a predetermined amount.

12. A means to monitor the operation of a smoke detecting device which has a light source for projecting light into an area which is shielded from outside light; a light sensing device and amplifier therefor, said light sensing device being positioned to receive light of said light source which is reflected by foreign particles in said shielded area and a first indicating device connected to said amplifier and constructed to operate responsive to the reception of light reflected from said shielded area; said monitoring means comprising a first means for producing a monitoring light beam and a second indicating device; said monitoring light beam being continuously impinged upon said light sensing device, the amplified output of said light indicating device due to said monitoring light beam being incapable of operating said first indicating device, said second indicating device being constructed to be operated responsive to the amplified output of said light indicating device due to said monitoring light beam.

13. A smoke detecting device for detecting the presence

of foreign particles in a volume of air which is to be circulated through a duct wherein the smoke detecting device has access to the air passing through said vent in a manner to exclude extraneous light from the duct, said smoke detecting device comprising a light source for projecting a first and second light beam, an interrupting means to interrupt said first light beam a first predetermined number of times per second and to interrupt said second light beam a second predetermined number of times per second, a photomultiplier, an A. C. amplifier, a narrow band pass circuit, a first and second indicating device and energizing means being connected to energize operation of said light source, photomultiplier and amplifier; said first light beam being directed with respect to the position of said photomultiplier to be impinged upon said photomultiplier only upon reflection and scattering from foreign particles in said air, said second light beam being directed to continuously impinge upon said photomultiplier; the output of said photomultiplier, being connected to the input of said A. C. amplifier, the output of said A. C. amplifier being passed through said narrow band pass circuit and thereafter to said first and second indicating devices; said first indicating device being constructed to be operative when said amplifier output contains at least the interrupted frequency of said first light beam, said second indicating device being constructed to be operative when said amplifier output contains at least the interrupted frequency of said second light beam, said second light beam being a monitoring light beam for assuring continuous operation of at least said light source, photomultiplier, amplifier and energizing means, said amplifier containing automatic gain control means for varying the amplification factor of said amplifier to maintain a substantially constant output of said amplifier.

14. A means to monitor the operation of a smoke de-
15. tecting device which has a light source for projecting
16. light into an area which is shielded from outside light; a
17. light sensing device and amplifier therefor, said light
18. sensing device being positioned to receive light of said
19. light source which is reflected by foreign particles in said
20. shielded area and a first indicating device connected to
21. said amplifier and constructed to operate responsive to the
22. reception of light reflected from said shielded area; said
23. monitoring means comprising a first means for producing
24. a monitoring light beam and a second indicating device;
25. said monitoring light beam being continuously impinged
26. upon said light sensing device, the amplified output of
27. said light indicating device due to said monitoring light
28. beam being incapable of operating said first indicating
29. device, said second indicating device being constructed to
30. be operated responsive to the amplified output of said
31. light indicating device due to said monitoring light beam,
32. said amplifier being constructed to maintain a substan-
33. tially constant output signal responsive to the input signal
34. due to said monitoring light beam.

15. A smoke detecting device for detecting the presence of smoke in air comprising a motor, a disk having apertures therein being driven by said motor, a light source, a photomultiplier, means to amplify the output of said photomultiplier and a first and second indicating device connected to said amplifier; said light source being constructed to provide a first and a second beam of light, said motor driven disk apertures being positioned relative to said first and second beam of light to synchronously interrupt said first beam of light in a first predetermined manner and to synchronously interrupt said second beam of light in a second predetermined manner upon rotation of said disk; said first interrupted beam of light being directed to be reflected into said photomultiplier when smoke is present in the air, said second interrupted beam of light being constantly impinged upon said photomultiplier; said first indicating device constructed to be operated when the amplified output of said photomultiplier is due to said first interrupted beam of light, said second

indicating device constructed to be operated when the amplified output of said photomultiplier is due to said second interrupted beam of light, said amplifying means being constructed to maintain a substantially constant output signal responsive to the input signal due to said monitoring light beam.

16. A means to monitor the operation of a smoke detecting device which has a light source for projecting a light into an area which is shielded from outside light; a light sensing device and amplifier therefor, said light sensing device being positioned to receive light of said light source which is reflected by foreign particles in said shielded area and a first indicating device connected to said amplifier and constructed to operate responsive to the reception of light reflected from said shielded area; said monitoring means comprising a first means for producing a monitoring light beam and a second indicating device; said monitoring light beam being continuously impinged upon said light sensing device, the amplified output of said light indicating device due to said monitoring light beam being incapable of operating said first indicating device, said second indicating device being constructed to be operated responsive to the amplified output of said light indicating device due to said monitoring light beam, said amplifier being constructed to maintain a substantially constant output signal responsive to the input signal due to said monitoring light beam; the sensitivity of said smoke detector being varied by varying the intensity of said monitoring light beam.

17. In a smoke detecting device having a light source for projecting a first and second beam of light into an area which is shielded from extraneous light; said first and second beams of light being varied according to a first and second mode; said first beam of light being directed to impinge directly upon a light sensitive device, said second beam of light being impinged upon said light sensitive device upon reflection from foreign particles in said shielded area; an amplifier being connected to amplify the output of said light sensitive device, the amplified output of said amplifier being connected to indicating devices operable in response to reception of signals being varied according to said first and second modes; and means for maintaining the output signal of said amplifier at a constant value when the input of said amplifier is varied.

18. In a smoke detecting device having a light source for projecting a first and second beam of light into an area which is shielded from extraneous light; said first and second beams of light being varied according to a first and second mode; said first beam of light being directed to impinge directly upon a light sensitive device, said

second beam of light being impinged upon said light sensitive device upon reflection from foreign particles in said shielded area; an amplifier being connected to amplify the output of said light sensitive device, the amplified output of said amplifier being connected to indicating devices operable in response to reception of signals being varied according to said first and second modes; and means for maintaining the output signal of said amplifier at a constant value when the input of said amplifier is varied, adjusting means being provided to vary the intensity of said monitoring light beam to thereby vary the amplification factor of said amplifier to a predetermined sensitivity.

19. In a device for detecting particles in an atmosphere comprising a light source, a light responsive means, an amplifier having two output devices, one of said output devices being a particle alarm device, the second being a supervisory device, a light circuit from said light source for impinging light on said light responsive means, means whereby said light circuit generates a predetermined signal in said amplifier circuit, means whereby said supervisory device is controlled by said predetermined signal, a second light circuit from said source to said light responsive means, means whereby said second light circuit generates a second predetermined signal in said amplifier and means whereby said particle alarm device is controlled by said second predetermined signal.

20. In a device for detecting particles in an atmosphere comprising a light source, means for synchronously interrupting said light source, a photomultiplier tube, an A.-C. amplifier, a narrow band filter and an indicating device; said photomultiplier being positioned to receive the light pulses of said interrupted light beam by reflection of said light pulses from particles appearing in said atmosphere to thereby impart a pulse output to said photomultiplier; said A.-C. amplifier being connected to amplify the pulse output of said photomultiplier; said narrow band circuit being connected to the output of said amplifier and constructed to pass the pulse frequency imparted thereto by the frequency of interruption of said light source; said indicating device being operated by the output of said narrow band filter.
